UNITED STATES PATENT OFFICE.

ARTHUR E. STOKER, OF BUFFALO, ILLINOIS.

VALVE-REMOVER.

1,082,917.

Specification of Letters Patent. Patented Dec. 30, 1913.

Application filed March 27, 1912. Serial No. 686,682.

To all whom it may concern:

Be it known that I, ARTHUR E. STOKER, a citizen of the United States, residing at Buffalo, in the county of Sangamon, State 5 of Illinois, have invented certain new and useful Improvements in Valve-Removers, of which the following is a description, reference being had to the accompanying drawing and to the figures of reference marked 10 thereon.

The invention relates to new and useful improvements in valve removers, that is, devices which are adapted for compressing the spring of the valve of an internal combustion engine so that the abutment for the spring attached to the valve stem may be removed and the valve lifted from its seat.

An object of the invention is to provide a valve remover of the above character, the 20 parts of which may be readily disassembled for the purpose of storing the same.

A further object of the invention is to provide a device of the above character with a compressing lever which is located directly in line with the spring of the valve, so that the spring may be compressed with little or no twisting of the parts of the valve remover.

In the drawings which show by way of 30 illustration one embodiment of the invention, Figure 1 is a vertical sectional view of a portion of an engine, showing the application of my valve remover, certain parts of the valve remover being shown in section; Fig. 2 is an enlarged detail view of the actuating parts and the supporting barrel therefor, certain parts being in section; Fig. 3 is a detail in perspective, showing one of the arms of the supporting frame; Fig. 4 is a 40 detail showing a modified form of joint for the members of the frame; Fig. 5 is a detail showing the manner of folding the frame.

In the drawings the engine cylinder 1 is provided with a valve chamber 2 in which 45 reciprocates a valve disk 3, having a valve stem 4. At the lower end the valve stem is formed with an opening 5 through which extends a pin or supporting plate 6. Said pin forms an abutment for the spring 7 which bears at its upper end against the lower face of the valve chamber. This 50 spring normally holds the valve seated, but allows the same to be lifted from its seat through the suction of the engine. This is 55 the ordinary form of spring-pressed valve,

and further description thereof is not thought necessary.

The present invention relates to a device for removing a valve of the above character. Said device consists of a frame 8 which is 60 formed as herein shown, with a single vertical portion 9 having a rectangular opening 10 adjacent each end thereof. An arm 11 is forked at its free end and is adapted to straddle or receive the valve stem so that 65 each side of the fork may engage the spring 7 on the valve stem. This arm 11 is formed with a contracted neck 12 which provides shoulders 13. Said arm also has a T-shaped head 14. The neck 12 is curved as clearly 70 shown in Fig. 1. The head 14 is substantially the same width as the length of the slot 10 so that said head may be turned longitudinally of the vertical member of the frame, and inserted through said rectangular opening, after which the arm is turned 75 so as to lie in a plane at right angles to the vertical member, and said head will hold said arm in this position and against any strain which tends to force the arm downward relative to the vertical member. It will readily be understood that this arm 11 may be turned in the opening in the vertical member and folded against said vertical member, as clearly shown in Fig. 5. Said 80 frame at its upper end is formed with a second arm 15 which is similar in all respects to the arm 11. This arm 15 is provided with a T-shaped head 16 which bears 85 against the outer face of the vertical member 9. The arm 15 at its free end is forked to receive a barrel 17. This barrel may be made of wood or any other suitable light material, and as herein shown, is provided with a plurality of spaced collars 18, 18, and 90 19. The space between the collar is reduced 95 so as to pass readily between the members of the fork in the upper arm 15 of the frame. The purpose of having a plurality of spaced collars is to allow for a certain range of adjustment of the barrel relative to the valve disk. Said barrel is provided with parallel spaced arms 20 at its upper end. Between 100 said arms is pivoted a cam lever 21 having a cam-shaped surface 22. Said barrel is 105 formed with a central opening 23. A plunger 24 extends through the opening and projects from the lower end of the barrel. The opening through the barrel at the upper end is enlarged to form a pocket and seat 110

for a spring 25. Said spring bears against a head 26 on the upper end of the plunger 24. This spring normally holds the plunger raised against the cam surface of the actuating lever 21.

In the operation of my device, the frame is positioned as shown in Fig. 1, and the forked end of the upper arm placed between two of the spaced collars so that the lower 10 end of the barrel and plunger are directly above and adjacent the valve disk. The lower arm of the frame is placed against the lower end of the spring of the valve. By the turning of the actuating lever 21, 15 the plunger will be carried into contact with the valve disk and a further movement of the lever will cause the barrel to rise, carrying with it the frame and the lower arm 11, which in turn compresses the spring 7 and 20 raises said spring away from the abutment or supporting pin 6 for the spring. This allows the supporting pin to be readily removed after which the actuating lever may be turned so as to allow the plunger to be withdrawn 25 within the barrel, the spring released, and the valve can therefore, be readily removed for the purpose of cleaning or regrinding.

In Fig. 4 of the drawings, I have shown a 30 slightly modified form of frame. In this view the vertical member 9' of the frame is provided with spaced ears 27 which ears are located a slight distance above the lower vertical member. The arm 11' is provided 35 with an ear 28 which extends between the ears 27 and is secured thereto by a pivot pin 29. The end of the arm 11' when the parts are unfolded, rests against the lower end of the vertical member and limits the 40 movement of the arm 11' relative to said vertical member.

From the above description it will be apparent that I have provided a valve remover having a frame which may be readily folded 45 so that the parts may be easily stored and the operating barrel containing the plunger may also be removed from the frame. Also when the parts are assembled the plunger and the actuating member therefor are directly 50 over the valve so that the thrust which compresses the spring valve is directly in

line with the valve, and any tendency to tilt or bind the parts, or to cause the tool to slip from the valve disk will be avoided.

It is obvious that minor changes in the details of construction and the arrangement of parts may be made, without departing from the spirit of the invention, as set forth in the appended claims.

Having thus particularly described my invention, what I claim as new and desire to secure by Letters Patent is:—

1. In a valve remover, the combination of a barrel, a plunger in said barrel, means for moving said plunger relative to said barrel, a frame including a vertical member, and folding arms carried thereby, one of said arms being adapted to removably engage the barrel and the other arm being adapted to engage the valve spring. 70

2. In a valve remover, the combination of a barrel, a plunger in said barrel, a lever having a cam surface adapted to engage said plunger, a frame including a vertical member, and folding arms attached thereto, one 75 of said arms being adapted to removably engage the barrel, and the other arm being adapted to engage the spring of the valve.

3. In a valve remover, the combination of a barrel having spaced collars, a plunger in 80 said barrel, a spring for lifting said plunger, a lever having a cam face for depressing said plunger, and a frame including a vertical member, and folding parallel arms attached thereto, one of said arms being 85 forked so as to receive the valve stem and engage the valve spring, and the other arm being forked to engage between the spaced collars on said barrel.

4. In a valve remover, the combination of 90 a barrel, a plunger in said barrel, a spring for lifting the plunger, a lever having a cam face for depressing the plunger, and a frame including an arm adapted to removably engage the barrel, and an arm adapted 95 to removably engage the spring of the valve.

In testimony whereof, I affix my signature, in the presence of two witnesses.

ARTHUR E. STOKER.
